[57] CLAIM

The ornamental design for a bank check, as shown and described.

DESCRIPTION

FIG. 1 is a top plan view of a bank check showing my new design;

FIG. 2 is a right side elevational view thereof, the left side elevational view being identical;

FIG. 3 is a front elevational view thereof, the rear elevational view being identical;

FIG. 4 is a bottom plan view thereof;

FIG. 5 is a top plan view of a second embodiment of FIG. 1;

FIG. 6 is a right side elevational view thereof, the left side elevational view being identical;

FIG. 7 is a front elevational view thereof, the rear elevational view being identical; and,

FIG. 8 is a bottom plan view thereof.

The broken lines shown are for illustrative purposes only and form no part of the claimed design.
